UNITED STATES PATENT OFFICE.

JAMES W. NELSON, OF NEW YORK, N. Y.

HYDRAULIC-PRESSURE-CONTROLLING MEANS.

No. 914,166.

Specification of Letters Patent.

Patented March 2, 1909.

Application filed January 20, 1908. Serial No. 411,612.

To all whom it may concern:

Be it known that I, JAMES W. NELSON, a citizen of the United States, and a resident of the city of New York, borough of Brooklyn, county of Kings, and State of New York, have invented certain new and useful Improvements in Hydraulic-Pressure-Controlling Means, of which the following is a specification.

10 This invention relates to means for controlling the generation and application of the pressure of hydraulic pumps, with particular reference to apparatus designed for the purpose of applying the pressure at a 15 point at some distance from the location of the pump or the pressure generating mechanism.

20 In a co-pending application, filed January 20, 1908, Ser. No. 411,613, I have shown and 25 described a pressure-controlling means of the same general character, but in that case the controlling device is adapted for use in connection with a pump of the single piston type.

25 The present invention contemplates the employment of a double or multiple piston pump, particularly adapted for use when it is desired to sacrifice power for speed in raising the ram or rams to contact with the 30 work or load, after which all but one of said pumps are rendered inoperative in order that there may be rendered available the maximum power of which the device is capable.

35 In the co-pending application aforesaid, I stated that one of the more particular objects of locating the pump and pressure valves in a member which is independently movable with respect to both pump and 40 ram, was to provide for the employment of two or more rams, operated by a single pump, and for the purposes of this description I have correspondingly shown the present invention as applied to a double or 45 multiple pump, the pressure of which is intended to be equally applied at two different points.

My invention will be more readily understood by reference to the accompanying 50 drawings forming a part of this specification in which—

Figure 1 is a diagrammatic view of the complete apparatus showing the pump and one of the rams in section; Fig. 2 is an 55 enlarged partly sectional plan view of the valve container, and Fig. 3 is a transverse section through the upper part of Fig. 2.

Referring now to the drawings in detail, numeral 11 refers to a pump cylinder having a central bore 12, the lower portion 13 of 60 which is reduced in diameter. A piston rod 14 carries the larger piston 15, operating in the upper and larger portion 12 of the pump bore, and projecting from the head of the piston 15 is the rod 16 carrying the smaller 65 piston 17 adapted to operate in the lower and smaller portion 13 of said pump bore. The piston rod 15 projects from the top of the cylinder 11, where it is preferably provided with suitable packing, and is pivoted 70 to the lever 18 fulcrumed at 19 to the bracket 20 carried by the cylinder 11. The pistons 15 and 17 may be provided with suitable packing, although this feature is not shown in the drawings. From the chamber 75 beneath the larger piston 15 leads a duct 21 to a coupling 22, by means of which said duct communicates with the pipe 23. A duct 24 similarly leads from the chamber below the smaller piston 17 through the coupling 25 80 to the pipe 26.

The valve box or container comprises a preferably cylindrical body 27, of suitable metal, which is bored to provide a chamber 28 threaded for the reception of a screw-plug 85 29 which seals said chamber. From this chamber 28 leads the longitudinal valve bore 29, the other end of which is sealed by means of the screw-plug 30. The bore 29 is increased in diameter a short distance from the 90 chamber 28 to provide a seat for the valve 31, which has a stem 32 extending upwardly and projecting into the chamber 28. In a similar manner, a seat is provided for the valve 33 which has a stem 34 which, when 95 said valves are seated, extends nearly but not quite to the valve 31. For the purpose of again reducing the size of the bore, and for other reasons, I prefer to employ a removable cylindrical plug 35 to provide a seat 100 for the valve 36, which has a stem 37 which, when said valves are seated, extends nearly but not quite to the valve 33. The valve 36 is preferably spring-seated, as shown. This valve member 27 is provided at one end with 105 the branching arms 38 and 39, each of which is preferably screw threaded at its end for the reception of the couplings 40 and 41, respectively, which serve to connect the pipes 23 and 26 with these arms. The arm 39 is pro- 110

vided with the longitudinal duct 42 open to the interior of the pipe 26 and communicating, through the lateral duct 43, with that portion of the bore 29 between the valves 33 and 36. The arm 38 is similarly provided with a duct 44 which provides communication between the pipe 23 and that portion of the bore 29 between the valves 31 and 33. I have shown the other end of the member 27 similarly provided with a pair of branching arms 45 and 46, having longitudinal ducts 47 and 48, respectively, both of said ducts being open to the chamber 49 below the valve 36. These ducts 47 and 48 communicate, through the couplings 50 and 51, with the pipes 52 and 53, respectively. The pipe 52 leads through the coupling 54 and the plug 55 to the chamber 56 below the ram 57 in the ram-cylinder 58. The pipe 53 leads in a similar manner to the pressure chamber underneath the ram 59 in the ram-cylinder 60, these ram members being identical in all material respects. The plug 29, sealing the chamber 28, is provided with the short shaft 61, carrying at its inner end the cam 62 located in co-operative positional relation to the upper end of the stem 32 of the valve 31. The other end of the shaft 61 is provided with a head 63 which is preferably slotted for the reception of the bearing-portion 64 of the lever 65 pivoted in said head. It will now be apparent that by means of said lever 65 the shaft 61 may be rotated and the cam thereby operated, first, to impinge against the stem 32 of the ram 31 and positively unseat said valve without, however, interfering with automatic operation of the valves 33 and 36; second, by continuing rotation of said shaft, to depress the stem 32 so that valve 31 impinges against the end of the stem 34 of the valve 33, thereby holding both of said valves off their seats without, however, interfering with automatic operation of the valve 36; or, third, rotation of said shaft may be continued until the cam has operated to successively unseat all of said valves and positively hold the same off their seats. The member 27 is further provided with a bore which leads from the chamber 28 laterally to the exterior of said member, said bore being preferably enlarged and screw-threaded within its outer end for the reception of the plug 66, which carries the cylindrical nipple 67 to which may be secured a rubber or other form of flexible tube or hose leading to any convenient source of liquid supply.

It will now be apparent that with the valve controlling lever 65 in the position indicated in Fig. 2, and all of the valves, therefore, capable of performing their automatic functions, the up-stroke of the pump lever 18 will cause the formation of partial vacuums in the chambers below the piston 16 and 17. The thus-generated inequality of pressure will cause the liquid to flow from the source

of supply through the connection 67, into the chamber 28, through the upper portion of the bore 29 and past the valve 31, where it is divided, a portion of the liquid passing through the duct 44 and the pipe 23 to the chamber below the larger piston, and the other portion opening and passing the valve 33 and entering the duct 43 from whence it passes into the pipe 26 and to the chamber below the smaller piston. Upon the down stroke of the pump-lever 18, the pressure from the larger piston, through the pipe 23, closes the valve 31, and the liquid forced through said pipe passes the valve 33 and joins the liquid entering through the duct 42, from the smaller piston. The combined pressure unseats the valve 36 and the liquid is divided between the ducts 47 and 48, thence flowing to the ram or pressure chambers. In this manner, the greatest speed which the pump is capable of developing may be utilized, and when the ram or rams have been raised to the point where they receive the full weight of the load, the valve controlling lever 65 may be operated to turn the shaft 61 and the cam 62 through an arc sufficient to unseat the valve 31, in the manner hereinbefore described, and hold the same off its seat. It will now be apparent that while the upstroke of the pump-lever 18 will have the same effect as under the conditions heretofore described, upon the down-stroke thereof, the valve 31 being now held off its seat, the liquid which flows through the duct 44, instead of unseating and passing the valve 33, will follow the path of least resistance and return past the open valve 31, through the upper portion of the bore 29 back to the chamber 28 and thence to the source of supply. Under these conditions, therefore, the liquid under pressure of the larger piston will flow idly back and forth between the larger pump chamber and the source of supply, and the smaller piston 17 alone is effectively operative, the liquid being forced thereby through the pipe 26 and the duct 42 into that portion of the bore 29 below the valve 33, and thence past the valve 36 to the pressure chamber or chambers.

It has been explained that one of the prime functions of this separate or individual valve container is to enable an operator near both of the rams (or near the ram, if but one is employed) and who is in position to note the progress and effect of the work being done, to dependably control the generated pressure irrespective to the location of the pump or the continuance of the pumping operation beyond the desired point. It may frequently become necessary to temporarily stop the generation of increased pressure, and with the employment of my invention, the operator at the rams may effect this result without the necessity of signaling to the operator or workmen at the pump. This he would do

by turning the lever 65 through an additional arc, thus causing the cam 62 to further depress the valve-stem 32 until the valve 31 has contacted with the stem 34 and unseated the valve 33. Under these conditions, although the pumping operation is continued, no liquid will be forced past the valve 36 inasmuch as the valves 33 and 3 are both open and the path of the least resistance, 10 from both ducts 42 and 44, is back into the chamber 28 and thence to the source of supply.

When it is desired to relieve the pressures in the ram chambers, for the purpose of 15 lowering the rams for removal or readjustment of the apparatus, the lever 65 is rotated through a still greater arc, whereby the cam 62 will operate through the stems 32 and 33 to unseat the valve 36 and hold all of said 20 valves off their seats. In this manner an open passage is provided from each of the ram chambers back to the source of supply, and the rams may be readily lowered, usually by their own weight, for the purposes mentioned. The pipes 23, 26, 52 and 53 are 25 preferably of copper and, therefore, sufficiently flexible to enable relative movement of any one of the thus-connected members with respect to another or others. In my 30 co-pending application aforesaid, it is explained that long continued periods of pressure tend to harden or temper copper pipe and attention is directed to the fact that the pipes 23 and 26, which are, as a rule, much 35 longer than the pipes 52 and 53, the valve-member 27 being intended to be located in immediate proximity to the ram or rams, are only under pressure during the down-stroke of the pump-pistons when the latter 40 are effectively operative.

As hereinbefore suggested, my invention may be equally satisfactorily employed where but one ram is necessary or desirable, and many other modifications of minor 45 details of the apparatus illustrated will doubtless readily suggest themselves to those skilled in the art to which it appertains. I therefore do not desire to limit my invention to the specific construction herein 50 shown and described.

I claim as new and desire to secure by Letters Patent:

1. In combination, a plurality of means for generating hydraulic pressures, means 55 apart therefrom for combining and controlling the generated pressures, and means for applying the pressures at a selective point.

2. In combination, a plurality of means for generating hydraulic pressures, means 60 apart therefrom for combining, controlling and distributing the generated pressures, and means for simultaneously applying the combined pressure at a plurality of selective points.

3. In combination, a plurality of means

having a common operating means for generating hydraulic pressures, means apart therefrom for selectively rendering effective one or all of said pressures, and controlling the resultant pressure, and means for applying said resultant pressure at a selective point. 70

4. In combination, a plurality of means having the common operative means for generating hydraulic pressures, means apart 75 therefrom for combining said pressures or rendering effective one thereof only and for controlling and distributing the resultant pressure, and means for simultaneously applying said resultant pressure at a plurality of 80 selective points.

5. In combination, a multiple pump and means apart therefrom for applying the generated pressures, the pump and pressure valves being located in an individually-mov- 85 able fitting.

6. In combination, a double pump, and means apart therefrom for applying the generated pressures, the pump and pressure valves being located in an individually-mov- 90 able fitting.

7. In combination, a multiple pump, means apart therefrom for applying the generated pressures, the pump and pressure valves being located in a fitting which is in- 95 dividually movable and which is provided with means for the control of said valves.

8. In combination, a multiple pump, means for applying the pressure generated thereby at a plurality of selective points, and 100 means apart from both pump and pressure-applying means for controlling both the generation and the application of pressure.

9. In combination, a multiple pump, means apart therefrom for applying the pressure generated thereby, and an individually-movable member interposed between said pump and said pressure-applying means in which member is mounted the pump and pressure valves. 105

10. In combination, a multiple pump, means apart therefrom for applying the pressure generated thereby, and an individually-movable member interposed between said pump and said pressure-applying means in 110 which member is mounted the pump and pressure valves and which is provided with means for their manual control.

11. In combination, a multiple pump, means apart therefrom for applying the pressure generated thereby at a plurality of selective points, and an individually-movable member interposed between said pump and said pressure-applying means in which member is mounted the pump and pressure valves 115 and which is provided with means for their manual control.

12. In combination, a multiple pump, a ram cylinder and ram, flexible connecting conduits therebetween, and a member lo- 120 125 130

- cated intermediate the ends of said conduits and common to all thereof in which member is located the pump and pressure valves.
13. In combination, a multiple pump, a ram, flexible fluid-transmitting means therebetween, and an individually-movable member in said transmitting means having provision for controlling flow to and from the pump between said member and the pump and to and from the ram between said member and the ram.
14. In combination, a multiple pump, a plurality of rams, flexible fluid-transmitting means therebetween, and an individually-movable member in said transmitting means having provision for controlling flow to and from the pump between said member and the pump and to and from the ram between said member and the ram.
15. In combination, a multiple pump, a ram, a flexible conduit from each pump chamber and to said ram, said conduits uniting in an individually-movable member and said member being provided with means for the control of the flow through said conduits.
16. In combination, a multiple pump, a plurality of rams, and a flexible conduit from each pump chamber and to each ram chamber, said conduits uniting in an individually-movable member and said member being provided with means for the control of the flow through said conduits.
17. In combination, a multiple pump, a plurality of rams, and a flexible conduit from each pump chamber and to each ram chamber, said conduits uniting in an individually-movable member and said member being provided with means for the supply of liquid to said conduits and means for the control of the duration and direction of flow therethrough.
18. In combination, a double pump, a ram, a flexible conduit from each pump chamber and to the ram chamber, said conduits uniting in an individually-movable member, said member being provided with means for the supply of liquid to said conduits and with means for rendering one or both of said pumps inoperative and for relieving the pressure in the ram chamber.
19. In combination, a double pump, a plurality of rams, a flexible conduit from each pump chamber and to each ram chamber, said conduits uniting in an individually-mov-

able member, said member being provided 55 with means for the supply of liquid to said conduits and with means for rendering one or both of said pumps inoperative and for relieving the pressures in the ram chambers.

20. In combination, a double pump, a ram, a flexible conduit from each pump chamber and to the ram chamber, said conduits uniting in an individually movable member, a series of suitable pump and pressure valves in said member, means for successively unseating 60 said valves in order, and means for supplying liquid to the pump chambers.

21. In combination, a double pump, a plurality of rams, a flexible conduit from each pump chamber and to each ram chamber, 70 said conduits uniting in an individually-movable member, a series of suitable pump and pressure valves in said member, means for unseating one or more of said valves to render one or both of said pumps inoperative 75 and relieve the pressure in the ram chambers, and means for supplying liquid to said pump chambers.

22. In combination, a double pump, a ram, a flexible conduit from each pump chamber 80 and to the ram chamber, said conduits uniting in an individually-movable member, a series of valves in said member, one controlling back-flow to one of said pumps, one controlling back-flow to the other pump, and one 85 controlling back-flow from the pressure chamber, and means for unseating positively one or more of said valves.

23. In combination, a double pump, a plurality of rams, a flexible conduit from each 90 pump chamber and to each ram chamber, said conduits uniting in an individually-movable member, a series of valves in said member, one checking back-flow to one of said pumps, one checking back-flow to the other 95 of said pumps, and the third checking back-flow from the pressure chambers, means for positively unseating one or more of said valves, and means for supplying liquid to the pump chambers.

In testimony of the foregoing, I have hereunto set my hand in the presence of two witnesses.

JAMES W. NELSON.
